Specification of Letters Patent. Patented Aug. 24, 1909.

Application filed July 25, 1903. Serial No. 166,966.

To all whom it may concern:

Be it known that I, SOLOMON TOWNSEND HOLLY, a citizen of the United States, residing at Los Angeles, in the county of Los Angeles and State of California, have invented new and useful Improvements in Turbine-Engines, of which the following is a specification.

This invention relates to a turbine engine or rotary motor adapted to be operated by expansive fluid, such as steam or compressed air, and it relates particularly to improvements on the rotary motor disclosed in my application Serial No. 50,739, filed Mar. 11, 15 1901.

The primary object of my invention is to provide an engine of this class of superior efficiency and capable of economically using expansive fluid at extremely high pressure.

20 A further object of the invention is to provide a construction which will combine great strength with comparative lightness, and in this connection a further object is to enable the machine to be built largely of 25 sheet metal, thereby obtaining the advantages resulting from the greater strength and uniformity of such metal and obviating the expense of large and complicated castings.

30 An object of such construction is also to provide for separability of the piston and casing into a plurality of elements, to facilitate assembling and taking apart.

A further object of my invention is to 35 provide improved means for adjusting and regulating the supply of expansive fluid to the motor.

The accompanying drawings illustrate the invention.

40 Figure I is a partly sectional end elevation of the engine. Fig. II is an axial section thereof. Fig. III is a fragmentary section of the vane carrying members of the piston, showing the method of attachment. Fig. IV 45 is an end view broken in a number of different planes to show more clearly the path of the operating fluid in passing through the engine. Fig. V is a detail section on the line V—V in Fig. II, showing a group of 50 steam inlets. Fig. VI is a detail section on the line VI—VI in Fig. II. Figs. VII and VIII are fragmentary views taken on the lines VII—VII, and VIII—VIII in Fig. II, looking in the direction of the arrow. Fig.

IX is a plan, with the top removed. Fig. X 55 is a sectional view of a part of the piston and casing, showing a different form of the invention. Fig. XI is a view on the line XI—XI in Fig. X.

1 designates, in a general way, a casing 60 which is mounted on a base 2, on which are also mounted the standards 3 for the bearings 4, wherein the shaft 5 of the motor is journaled. The rotary piston, designated in a general way at 6, is fast on this shaft, 65 within the casing 1.

An annular pressure chamber 7 is formed in the casing 1, around the circumference thereof, and is formed in its inner wall 8 with ports 9 opening inwardly into the 70 working chamber wherein the piston 6 rotates. Said piston has a central series of buckets around its circumference, the inlets 10 of said buckets being in the plane of the ports aforesaid, and the said buckets being 75 provided with outlets 11 leading obliquely outward and backward on each side of the inlets. On each side of this central series of buckets on the piston are provided one or more circular series of vanes 12 connected 80 to and moving with the piston. Annular webs, flanges or supports 14 are fixed to and project inwardly from the casing or frame 1, 85 extending on each side of the piston, and support a plurality of circular series of vanes 15 arranged in concentric circles with intervening annular spaces for the reception of corresponding series of vanes 16 on the 90 piston. Annular webs 14 and the inner wall of the pressure chamber form a chamber inclosing the piston. Concave faces or corners 17 of the flanges serve to direct inwardly the fluid coming from the circumferential series of vanes 13, to force it toward the lateral series of vanes 16. All the moving vanes are directed backward, so as to deflect the impelling fluid accordingly, 95 while all the fixed vanes are reversely directed, so as to cause the fluid to resume a forward direction of movement for impact in proper manner on the next series of vanes.

The expansive fluid leaving the ports 9 at a high speed and with considerable pressure, enters the inlets 10 of the buckets and strikes the inner ends or abutments thereof, giving an impulse to the piston, then pass-

ing obliquely backward by the outlets 11 it gives by reaction a further impulse, and in such successive deflection by the successive series of moving vanes a further impulse is given the fluid being finally discharged at the annular spaces between the flanges 14 and the sides of the piston.

The piston is of relatively large diameter compared to its axial length or thickness, so as to give a high peripheral velocity, with a moderate shaft velocity. With such a construction the central series of buckets will, owing to their high speed, utilize a large portion of the energy of the fluid at the first impact before there is any substantial loss by friction, and the peripheral series of vanes are correspondingly effective in producing power with a minimum of frictional loss. In order, however, to keep the bulk and weight of the machine within moderate bounds, I provide only a few of such peripheral series of vanes, and deflect the fluid to act against the series of vanes on the side of the piston, thereby utilizing the large diameter of the piston to accommodate a large number of series of vanes, to give the requisite compounding effect.

A valve ring 18 is mounted within the annular pressure chamber 7, surrounding or embracing the inner wall 8 thereof, and having ports 9 aforesaid to control the admission of fluid pressure to the piston. For operating this valve ring 18 I have shown segment racks 20 on said ring, segmental toothed arms 21 engaging said racks and carried by rock shafts 22 pivoted in casing 1 and extending through one side of said casing, arms 23 on the outer ends of said shafts 22 and a bar 24 pivotally connected to said arms 23. One or both of said arms 23 is provided with a handle 25 by which the arms may be operated to turn the ring through the agency of the segment devices aforesaid. Valve ring 18 is desirably split or cut, the two ends thereof being connected by slip joint 26, to provide a slight play or movement and allow for contraction and expansion while permitting the valve ring to be pressed tightly upon its seat by the pressure in chamber 7.

The ends are overlapped, each end being of a reduced thickness, and one of them slotted longitudinally as at 95 and the other one provided with a stud 96 which projects through the slot. A screw 97 and a washer 98 are provided for holding the overlapping portion of the ring together.

Casing 1 is desirably constructed with disk-shaped side walls 27 and an interposed ring 28 which extends into annular seats 29 in the side walls 27, and is fastened thereto by screws 30. Pressure chamber 7 is formed in said ring 28, which is also formed with intake 31 and outlet 32 for said chamber. A ring 33 fitting within an inturned flange 34

on one side of the pressure chamber has a lateral flange 8 forming the inner wall of the pressure chamber, and valve chamber, and a ring 35 fits within an inturned flange 34 on the other side of said pressure chamber, the other side of the ring 28 abutting against the flange 8 to close the other side of the valve chamber. Rings 36 within the rings 33, 35, bear against shoulders 38 thereon. On the outer side of each of the rings 33, 35, are rings 37 bearing against said rings 33, 35, and against inturned flanges 34, and outside of these rings are the annular webs or vane-supports 14, all these parts being fastened together and to the ring 28 by bolts 39, 40. Bolts 39 clamp the rings 37 against flanges 34, said bolts passing through parts 14, 37, 35 and 33. Sleeves 41 act as distance pieces for rings 33, 35. Bolts 40 pass through parts 14, 37, 36, 33, 35. Said bolts 39, 40, have nuts at each end, and it will be seen that with the described construction, either side wall of the engine may be removed and the elements 14, 37 and 35 or 33 may then be removed in succession on that side of the engine without disturbing any parts on the other side. Rings 37 carry series of vanes 12 above referred to and other series of vanes 12 are carried by rings 36.

The ports or openings 9 in flange 8 are desirably arranged in groups, each group being of a length substantially equal to the length of the ports 19 of valve ring 18. In order to give a finer graduation as the power is more turned off these ports 9 should be of progressively smaller size in the direction of movement of the valve and to this end thimbles or sleeves 109 are inserted in the openings 9, such openings being of equal size and the thimbles having bores of different size to give the desired graduation of said area. By use of different sizes of sleeves 109, the same engine may be adjusted to any desired steam capacity and power, up to a certain maximum. The openings 9 taper inwardly, and the sleeves 109 taper correspondingly on the outside so that on slipping them into the openings they will be retained in place by the inwardly acting pressure.

The construction of parts herein shown, whereby the steam is cut off at the nozzle or outlet to the piston wheel, by closing progressively a gradually varying number of the series of ports, is of especial advantage in connection with the regulation of the engine. When regulation is effected by a throttle, more or less loss results due to loss of pressure in passing through the throttle, but when the regulation is effected by closing the jet orifices themselves, the amount of steam passing and energy developed may be controlled without any wire-drawing or loss of pressure and efficiency.

The drawings show a governor operated

by the engine and controlling the valve ring 18. The governor is connected to the shaft 5 by the worm 44 upon the shaft 5, the worm-wheel 45 meshing with the worm 44 and carried by the shaft 46, and the bevel gear 47 meshing with the bevel gear 48 on the shaft for operating the governor.

Piston 6 is built up of separable elements so as to enable the parts thereof to be readily 10 assembled and taken apart and to provide a light and strong construction. A hub 73 is fastened on the shaft 5 being, for example, supported between a cone-shoulder 74 on the shaft and a nut 75 screwing in a threaded 15 portion of the shaft. Two disks 76 desirably of sheet metal fastened to the hub by screws 77, are dished so that their peripheral portions are closer together than their parts that engage the hub, and a ring 78 is interposed between said disks at their peripheries and fastened thereto by screws 79. The inlets 10 of the buckets are formed in this ring, as shown in Figs. V and VI, a series of holes 80 being bored through this ring parallel to the axis of the piston to form the abutments of the buckets, and inlets 10 being slots cut obliquely outward from these holes to the periphery, and flaring at their outer ends so that the intervening metal parts or 20 projections 81 taper to sharp edges at their outer ends. Holes 11 are bored obliquely outward through each of the side disks 76 to form the outlets of the buckets, these holes extending from the holes 80, when the parts 25 are assembled. The circumferential distance between the bucket inlets 10, is less than the circumferential distance of ports 9, thereby obtaining an even or distributed effect on the piston. In this construction of this portion 30 of the wheel the inlets 10, or fluid-receiving passages extend inwardly and forwardly at a gradually increasing depth in the direction in which the wheel is to rotate and the outlets extend from the forward ends of the 35 inlets in duplicate branches outwardly and rearwardly at a substantially uniform depth to the side surfaces of the wheel.

To support the lateral vanes 16 on the piston, disks 83 desirably of sheet metal are 40 fastened by screws 84 to the hub 73, and are provided with annular seats 85 which receive rings 86 carrying the vanes aforesaid, said rings being centered by said seats and fastened in place by screws 87. Between the 45 peripheral portions of the disks 83 and 76 on each side, is interposed a ring 88, carrying the series of vanes 13. Screws 89, pass through these rings 88 on each side into engagement with the central piston element 76, 78, and screws 90 fasten disks 83 to rings 88. By this construction, the lateral portions 83, 88, of the piston, on each side, are readily removable independently of each other and of the central part 76, 78, of the piston. The 55 construction of such central part, with the

convergently dished side disks 76, give a maximum of strength and stiffness for a given weight, and the construction of the piston as a whole with the sheet metal disks 76, 83, conduces to the same.

The piston structure is desirably made of steel, and the valve chamber ring 33 is desirably of a material having a greater expansibility than steel, for example, brass, to prevent binding of the parts when the engine 75 is heated by the steam.

The series of fixed vanes 15 are desirably supported and centered in similar manner in seats 92 in the inner faces of webs 14, being fastened therein by screws 93.

In case the engine is used with steam or compressed air and exhausts directly into the atmosphere, the casing 1 may be open at the center where the shaft passes through, but in some cases, as in working with steam and with a condenser, and a consequent partial vacuum in the casing, stuffing boxes 91 will be placed in the casing walls 27 where the shaft 5 passes therethrough and stuffing boxes will be provided for rock shafts 22, 80 where they pass. Such boxes will also be required when pressure exists within the chamber, for example, when working with compressed air and expanding the air from high pressure to a pressure intermediate between such high pressure and atmospheric pressure.

On account of the comparative freedom from frictional resistance in this engine, both in the bearings and in the fluid passages, and particularly on account of the fact that the greater part of the available energy can be taken up from the fluid in the first few impacts at the periphery, before there is an opportunity for substantial frictional loss, the engine is particularly adapted for use as a heat abstracting means in refrigerating apparatus wherein compressed gas is caused to perform external work, in passing through an engine which reduces its 100 pressure and temperature.

Owing to the fact that the steam expands as it passes from the inlet to the outlet, and also owing to the fact that the circumferential area decreases toward the center, I prefer to give the lateral vanes 16 a greater area than the radial vanes 12, as by making them longer, and to make the vanes of the inner or smaller rows longer or wider than those in the outer or larger rows. In this manner 110 the steam can move forward with sufficient speed to avoid back pressure, and as the peripheral speed of the vanes decreases as the center of the piston is approached, the gradually slowing steam will still exert its effectiveness upon the vanes. This principle 115 may be further carried out by constructing the engine as shown in Fig. 10, with the side plates 83 dished inwardly so as to contact at their central portions with the reversely 120

dished plates or disks 76 and to be fastened to the hub 73 by the same screws 77 that fasten the plates 76, the peripheral vane carrying rings, here shown as more than two in number, being clamped between the outer disks 83 and the inner disks 76 as above described. The space between the rotary disks 83 and front webs 14 is thus made wider toward the center and the successive fixed 10 and moving vanes 15, 16, can thus be made progressively wider as the center is approached, to allow for the greater volume and lower speed of the steam. The outer webs 14 may also be flared outwardly as 15 shown so as to increase this widening effect. In Fig. 11 I have shown the vanes as straight, and inclined to the direction of rotation in proper manner to deflect, and receive power from, the currents of steam.

20 The perforations 19 in the valve ring are of such size and are located at such a distance apart that when they register with the groups of ports 9 the steam will have a free and unobstructed passage to the ports, and 25 when the ring is rotated, the passage to the ports can be partly or wholly closed as may be desired. The openings in the valve ring, as well as in the inlet openings through the port ring, are arranged at an angle or substantially tangential to the periphery of the 30 piston so as to deliver the steam against the abutments in the most effective manner.

With an engine constructed as above described, it is evident that it can be run at an 35 enormous peripheral velocity, the steam or other medium being delivered at the periphery, where it may exert the greatest leverage and may act on parts moving at the highest speed, and therefore most effective in taking 40 up the energy of the fluid. From there it passes, with ever decreasing speed, toward the center, where the peripheral speed of the piston is less, until finally it leaves the shell and casing with but little effective power re- 45 maining in it. By increasing the diameter of the engine, its power can be increased greatly without detracting from its effectiveness by reason of objectionable features. And by delivering the steam at the peripheral 50 center of the piston and distributing it equally in both directions laterally, all end thrust or pressure is avoided.

What I claim and desire to secure by Letters-Patent of the United States is:—

55 1. A motor comprising a pressure chamber having ports adapted to deliver expansive fluid at a high velocity, a rotary piston having a central series of circumferential buckets with outlets on each side of their inlets, concentric series of fixed and movable vanes, the movable vanes being connected to and moving with the rotary piston and arranged in circles of progressively smaller diameter, deflecting means to conduct the 60 fluid from the outlet of the central series of

buckets to the inlet of the radial series of vanes and fixed deflecting means adapted to deflect the fluid inwardly to operate upon said concentric series of vanes.

2. A motor comprising a casing having a 70 pressure chamber provided with ports adapted to deliver expansive fluid at a high velocity, a rotary piston having a central series of circumferential buckets with outlets on each side of their inlets, circular series of 75 fixed and movable vanes, connected respectively to the casing and to the rotary piston and arranged on each side of the said outlets, fixed deflecting means adapted to deflect inwardly, the expansive fluid from such 80 vanes and circular series of fixed and moving vanes arranged concentrically, each within the preceding series and connected respectively to the casing and to the rotary piston.

85

3. A motor comprising a casing having an annular pressure chamber provided with inwardly directed ports adapted to deliver expansive fluid at high velocity, a rotary piston provided with a central series of circumferential buckets having outlets on each side of their inlets, circumferential vanes on each side of, and arranged in circles of equal diameter with, said central series of buckets, and vanes on the sides of the rotary piston 90 arranged in concentric circles, and series of fixed vanes located between the series of piston vanes.

95

4. A turbine piston comprising two disk members having series of oblique perforations, and an interposed member having radially inclined slots connecting said perforations.

100

5. A turbine piston comprising two disk members having series of oblique perforations, and an interposed member having radially inclined slots with enlarged inner portions connecting said perforations.

105

6. A turbine piston comprising a hub, two disk members attached thereto, and dished to 110 approach each other at their peripheries, a continuous ring interposed between said disk members at their peripheries, and means rigidly connecting the peripheral portions of the disk members to each other and to the 115 interposed ring.

7. A turbine for expansive fluid comprising a casing with an annular pressure chamber provided with a plurality of ports in its inner wall, a valve ring surrounding 120 such inner wall and having ports, and a rotary piston having a plurality of buckets adapted to receive the expansive fluid from the fixed ports, the number of said buckets and of the fixed ports being greater than 125 the number of valve ports.

8. In a turbine, a plurality of nozzle openings arranged in series, and sleeves fitting in said openings, said sleeves having ports and the ports of each series being graduated 130

in size, and means for closing said ports progressively.

9. A turbine comprising a casing with an annular pressure chamber provided with 5 ports in its inner wall, a piston having a central series of buckets around its circumference, the inlets of said buckets being in the plane of the ports aforesaid, and the outlets of the buckets leading obliquely outward 10 and backward on each side of the inlets, a valve ring surrounding such inner wall and having ports, and means for operating said valve ring, comprising rock shafts extending through the walls of the casing, operating 15 means connected to said rock shafts, arms carried by said rock shafts, and segment gears on the valve ring, engaging with one another.

10. In a turbine, a casing with an annular 20 pressure chamber, having an annular internal flange in each side, a ring bearing against the flange on one side of the pressure chamber and having a lateral flange provided with ports, and a ring abutting 25 against the aforesaid ring and flange.

11. A piston for rotary engines consisting of a substantially cylindrical body portion and disks secured to the ends thereof, the body and the disks being each provided with 30 deflector vanes at its periphery and each of the disks being provided with circularly arranged vanes projecting outwardly thereupon.

12. In a rotary engine, a casing, a piston 35 rotatably mounted therein, and radially and laterally extending vanes, and means for

causing the steam to pass first laterally and then radially relatively to the piston.

13. In a rotary engine, a casing, a piston rotatably mounted therein and provided 40 with rows of radially and laterally extending vanes, and a shell around the piston, the interior of which is provided with rows of radially and laterally arranged vanes, the rows of the shell alternating with the rows 45 of the piston, and the said casing being provided with inlet and outlet and deflecting means to direct the operating fluid successively against the radially and laterally extending vanes. 50

14. A rotary piston member adjusted to be actuated by impact of an expansive fluid, a pressure chamber surrounding said piston member and provided with a plurality of port openings adjacent to said piston member, means for supplying expansive fluid to said pressure chamber, a valve ring provided with a plurality of ports arranged in series, the ports of each series being graduated in size and adapted to close said port openings 60 progressively, and engine-operated governor means controlling said valve ring. 55

In testimony whereof, I have signed my name to this specification in the presence of two subscribing witnesses, at Los Angeles, in 65 the county of Los Angeles and State of California, this 16th day of July, 1903.

SOLOMON TOWNSEND HOLLY.
